UNITED STATES PATENT OFFICE.

ALFRED DUNHILL, OF LONDON, ENGLAND.

APPARATUS FOR OBTAINING KALEIDOSCOPIC LIGHTING EFFECTS.

Application filed June 11, 1926, Serial No. 115,224, and in Great Britain January 20, 1926.

Apparatus for obtaining varying color lighting effects for decorative and advertising purposes are well known and my present invention relates to improvements in that 5 class of apparatus comprising a casing or stand within which is mounted a rotating disc that is composed of a multiplicity of glass sectors through which the light rays from an electric lamp are projected and emitted from 10 an aperture formed in the top of the casing over which a glass spherical globe or other object to be illuminated is stood so that as the disc is rotated varying color rays are emitted due to the different sectors of the disc coinciding with the aperture in the aforesaid casing. Obviously by these means only a 15 sequence of color rays are emitted or projected.

The present improvements have reference 20 particularly to this class of apparatus and for the purpose of obtaining a kaleidoscopic, chromatic or ever varying color lighting effect of the hollow translucent body placed over the aperture in the casing, instead of employing a single disc preferably three such 25 discs are employed each of such discs being rotated at varying speeds so that by such means an ever changing or varying blending of the color rays are secured and most pleasing illuminating effects are obtained.

30 The mechanism for effecting the rotation of the several discs, which may be two or more in number, that is to say not necessarily three as suggested above, may be of the ordinary clockwork, spring motor driven or a small 35 electric motor connected with suitable reducing gear whereby very slow rotation of the several concentrically superimposed discs at varying speeds may be obtained.

To still further improve the varying color 40 lighting effect beneath or within the aforesaid spherical or other suitably shaped translucent globe may be placed over or upon the glazed aperture in the casing through which the light rays are emitted a glass sphere of suitable size, a glass spheroidal body, prismatic lens or other suitably shaped glass body preferably with a hemispherical base that may be 45 stationary or made to traverse across the glazed aperture aforesaid, whereby the colored light rays are so completely deflected and diffused as to produce an extraordinary lighting effect of the whole of the translucent globe within which the glass spheroidal body is housed, due to the rotation of the 50 discs as aforesaid.

In order that my invention may be readily

understood reference may now be had to the accompanying sheet of drawings in which:—

Figure 1 is a cross sectional elevation of an apparatus of the type described with my improvements applied thereto.

Figure 2 is a plan of Figure 1 showing the interior of the apparatus with the lid or cover of the casing removed.

Referring to the drawing, in which similar reference characters relate to like parts in both the figures, *a* is the base, *b* the lid or cover of the decorative case enclosing the apparatus.

The mechanism consists of the spring 70 motor *c* which drives through suitable reduction gearing *d* the central standard or spindle *e* the motor being governed by the vane *g* and wound up by the removable handle *f* in the ordinary manner.

In the apparatus illustrated by way of example the improved mechanism consists of the three discs *h* *i* and *j* independently mounted and rotatable upon the central spindle *e*. The spur wheel *h* rotates the spindle *m* supported in a vertical position by the bracket *n* said spindle *m* carrying three spur wheels of different diameters apart from that meshing with the wheel *h*. These spur wheels respectively mesh with the spur wheels *h'* *i'* *j'* which 85 by means of hollow concentric bushes rotate the discs *h* *i* and *j*. It will thus be seen that when the central spindle *e* rotates the spindle *m* and the discs *h* *i* and *j* are independently rotated at different speeds whereby the framework of the several discs containing the colored glass segments are caused to pass over one another in a constantly changing manner thus emitting an ever changing colored light beam through the aperture *p* in the lid of 95 the cover *b* due to the lamp *o*.

Over the aperture *p* is placed a suitably shaped translucent globe *q* indicated in dotted lines preferably spherical but may be of other shape and inside this globe may be 100 placed a glass hemisphere *r* or a glass spheroidal body, prismatic lens or other suitably shaped glass body whereby the colored light rays are so diffused as to produce a very pleasing lighting effect of the translucent globe *q* 105 due to the rotation of the discs as above described. The supplementary light diffusing element or glass body *r* instead of being stationary as shown may be caused to traverse the aperture *p* by any convenient means thus 110 still further diffusing the light rays emitted.

The above description has been limited to

what may be termed portable decorative apparatus but it will be obvious that by suitable distribution of the said rotatable colored glass segments with or without the glass hemispherical or glass spheroidal body the apparatus may be employed for producing very striking theatrical stage lighting effects without departing from the nature of the said invention.

10 What I claim is:-

1. In a device of the kind described, a motor frame, a motor driven spindle supported therein, a series of concentric bushings nested one within the other on said spindle and having their ends in vertically spaced relation, gearing connecting the spindle and respective bushings to cause the latter to revolve at different speeds from each other and from the spindle, a series of disks one of which is fixed 15 on the spindle to revolve therewith and the others of which are fixed on respective bushings to revolve therewith, said disks being each provided with a series of transparent differently colored sectors, the disks being of 20 uniform diameters, a casing covering said disks and having an opening therein to one side of the axis of the spindle and beneath 25

which said disks rotate, and a light source supported within the casing beneath said opening.

2. In a device of the kind described, a motor frame, a motor driven spindle supported therein, a series of concentric bushings nested one within the other on said spindle and having their ends in vertically spaced relation, 30 gearing connecting the spindle and respective bushing to cause the latter to revolve at different speeds from each other and from the spindle, a series of disks one of which is fixed on the spindle to revolve therewith and the others of which are fixed on respective bushings to revolve therewith, said disks being each provided with a series of transparent 35 differently colored sectors, the disks being of uniform diameters, a casing covering said disks and having an opening therein to one side of the axis of the spindle and beneath which said disks rotate, a light source supported within the casing beneath said opening, and a light diffusing body of transparent 40 material positioned on said casing immediately over the opening therein.

In testimony whereof I affix my signature.

ALFRED DUNHILL.
